UNITED STATES PATENT OFFICE.

WILLIAM MARR WARD, OF GRAND BLANC, MICHIGAN.

DEVICE FOR OPERATING CARRIAGE-TOPS.

SPECIFICATION forming part of Letters Patent No. 372,948, dated November 8, 1887.

Application filed March 9, 1887. Serial No. 230,315. (No model.)

To all whom it may concern:

Be it known that I, WILLIAM MARR WARD, a citizen of the United States, and a resident of Grand Blanc, in the county of Genesee and State of Michigan, have invented certain new and useful Improvements in Devices for Raising and Lowering Carriage-Tops; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 My invention relates to a device for raising and lowering carriage-tops, and has for its object to provide a simple, convenient, and inexpensive means by which this result is accomplished by the occupant of the carriage while 20 sitting in a normal position on the seat, thus obviating the necessity of either having to alight or be obliged to manipulate the braces at the great inconvenience of reaching out of the carriage and causing the braces to "break 25 joint" first on one side and then upon the other in lowering, and in locking the joint when raised.

As is well known, the position of the braces, located as they are at some distance back of 30 the front bow of the carriage-top, renders it exceedingly difficult of manipulation and requires the occupant to assume a position that is at once awkward and uncomfortable. By the use of my invention these objections are 35 entirely overcome, and the top can be readily raised or lowered by means of a lever within easy reach of the occupant of the carriage, with no inconvenience, and requiring the exercise of but little manual labor.

40 In the drawings, Figures 1 and 3 are side elevations showing, respectively, the top raised and lowered, the front side being removed to show the interior of the carriage. Fig. 2 is a view in elevation, showing the back of the top 45 with the rocking bar and arms, the arms being connected to the braces of the carriage-top. Fig. 4 is a detail view showing the mode of fastening the arms to the sliding yokes that embrace the top braces. Figs. 5, 6, and 7 are 50 diagrammatic views of modified constructions of the sliding yokes. Fig. 8 is a perspective

of one of the hangers in which is journaled the rocking bar.

A designates the carriage-box; B, the seat; C, the top; D and E, the braces. F is the stud 55 upon which the braces are journaled.

So far I have described the ordinary construction of top carriages in general use.

The preferred way of applying my invention is by means of hangers K, rigidly mounted 60 upon studs F, either by squaring the stud and forming a hanger with a square hole and slipping the hanger upon the studs back of the cushion upon which the bows rest when the top is drawn; or this may be accomplished by 65 having both round and fastening by a set-screw; or an ordinary spline may be employed, so that the hanger is rigid upon the stud. In the projecting end of hangers K are round holes or bearings L, in which is journaled a rocking bar, 70 G, having arms H at right angles thereto.

To the braces E are clamped sliding yokes, of the construction shown in either Figs. 4, 5, 6, or 7, these modified forms being shown to illustrate some of the various means of attachment that may be employed without departing from the spirit of my invention, it being optional of what metal these yokes are constructed, as they may be of brass or iron, or iron lined with brass, copper, or Babbitt metal. 80

In Fig. 4 the yoke I is made in two parts and held together by means of screw or bolt i. The brace H is slipped onto the bolt or journal and held by means of nut m, it being understood that this shoulder is formed on the 85 inner part of the bolt or journal against which the arm H rests.

If necessary, washers may be placed between the nut m and arm H.

Fig. 5 shows a form of construction in which 90 the yoke is formed of one piece. The portion I², that embraces the brace, is placed in position and the bifurcated journal or bolt is pressed together and the arm placed thereon. In Fig. 6 the construction is simplified, being merely 95 a bifurcated yoke, the part I³ embracing the brace on three sides and being attached to the arm H, as in the previously-described constructions.

Fig. 7 represents a construction in which the 100 yoke is formed of two parts held together by being dovetailed, the part I⁴ being rigid with

the bolt or journal *l*, and the part *n* being held in place by slipping the same in position after the brace is within. In Fig. 7 is also shown the nut, which is of ordinary construction, employed in holding the brace in position.

The yoke, after being loosely attached to the brace *E*—that is, with sufficient looseness to admit of its sliding freely upon the brace without rattling—is attached to arm *H*. To the rocking bar *G*, between the seat-rail and the bows of the top, is rigidly attached lever *J*, being by this construction within easy reach of the occupant of the carriage.

The operation is as follows: When it is desired to lower the top, the lever *J* is grasped and brought from its normally-horizontal position to a vertical one, thereby revolving the rocking bar *G* and arms *H*, the yokes sliding freely upon braces *E*, and the top is easily lowered. In raising, the operation is reversed, it only being necessary to bring the lever from a vertical to a horizontal position.

Having thus fully described my invention, what I claim, and desire to secure by Letters Patent, is—

25 1. In a device for raising and lowering carriage-tops, a right-angled rocking bar journaled in hangers back of the seat, having the two angled portions embracing the braces, and

a lever at right angles with the angled portions, as and for the purpose set forth.

2. In a device for raising and lowering carriage-tops, a right-angled rocking bar journaled in hangers back of the seat, in combination with separable yokes embracing the braces, as and for the purpose set forth.

3. In a device for raising and lowering carriage-tops, a separable sliding yoke loosely attached to the carriage-brace, as and for the purpose set forth.

4. In a device for raising and lowering carriage-tops, a rocking bar provided with arms at each end, said arms being connected movably to the braces of the carriage-top, and means for rocking said bar, as and for the purpose set forth.

5. A device for raising and lowering carriage-tops, consisting of hangers *K*, rocking bar *G*, arms *H*, attached to braces *E* by sliding connections, and lever *J*, substantially as shown and described.

In testimony that I claim the foregoing as my own I hereby affix my signature in presence of two witnesses.

WILLIAM MARR WARD.
